United States Patent Office

Des. 228,336

Patented Sept. 11, 1973

228,336

ROLLING PIN OR THE LIKE

Hugh N. Pace, 3516 Poole Road,
Raleigh, N.C. 27610

Filed Jan. 11, 1971, Ser. No. 105,767

Term of patent 14 years

Int. Cl. D7—04

U.S. Cl. D7—99

FIG. 1

FIG. 2

FIG. 3

FIG. 4

FIG. 1 is an elevational view of a rolling pin or the like showing my new design;

FIG. 2 is an elevational view rotated 120 degrees from the view shown in FIG. 1;

FIG. 3 is an elevational view rotated an additional 120 degrees from the view shown in FIG. 2; and

FIG. 4 is an end elevational view, the opposite end being substantially identical to that shown.

I claim:

The ornamental design for a rolling pin or the like, as shown and described.
